HINGE GUARD

Noble E. Peeler, St. Paul, Minn.

Application January 17, 1950, Serial No. 138,966

1 Claim. (Cl. 16—86)

1

My invention relates to a hinge guard.

A primary object of the invention is to provide a guard for the hinges of doors, the use of which will prevent injury to fingers and hands, as well as other objects which sometimes are crushed when inserted in door jambs.

A further object is to provide a hinge guard of the above-mentioned character which will also function as a snubber or stop to limit the swinging movement of a door.

A further object is to provide a hinge guard of the above-mentioned character formed of rubber or similar material, and having a novel shape or contour in transverse cross-section, such contour resulting in a novel mode of operation or movement of the hinge guard when the door with which it is associated is opened and closed.

A further object of the invention is to provide a hinge guard of the above-mentioned character which is resilient and somewhat flexible, so that it will lie substantially flat against the door to which it is applied, when such door is closed.

A still further object is to provide a hinge guard of the above-mentioned character which is capable of a wide variety of applications, and which may be formed to blend in color and shape with adjacent door frames, decorative moldings and the like.

A further object of the invention is to provide a hinge guard for use upon a wide variety of hinge joints, the guard being highly simplified, compact, extremely sturdy and durable and relatively inexpensive to make.

Other objects and advantages of the invention will be apparent during the course of the following description.

In the accompanying drawing forming a part of this application, and in which like numerals are employed to designate like parts throughout the same:

Figure 1 is a fragmentary perspective view of a short section of a hinge guard and door snubber embodying the invention;

Figure 2 is a fragmentary horizontal sectional view through a door and door jamb, illustrating the application of, as well as the mode of operation of the hinge guard;

Figure 3 is a fragmentary side elevational view, partly diagrammatic and drawn on a reduced scale, for further illustrating the application of the hinge guard to a door; and

Figure 4 is a fragmentary plan view, partly diagrammatic, illustrating a slight modification of the construction and application of the hinge guard.

2

In the drawing, where, for the purpose of illustration, are shown preferred embodiments of my invention, attention is directed first to Figures 1 to 3, inclusive, wherein the numeral 10 designates one vertical side of a door frame extending laterally beyond one side of an adjacent wall 11. A horizontally swinging door 12 is hinged connected with a jamb 16 of the door frame 10 at its vertical edge adjacent to the wall 11 by means of hinges 13. The hinges include the usual flat hinge leaves 14 secured flush with the inner vertical edge 15 of the door 12 and with the jamb 16 of the door frame 10. As shown clearly in Figure 2, the door 12 is swingable upon the hinges 13 from the open position shown in full lines, wherein the door may be substantially parallel with the outer side of the wall 11, to the closed position shown in dotted lines, wherein the door extends at right angles to the jamb 16 and the edge 15 of the door overlaps the jamb 16 with the hinge leaves folded upon each other in the usual manner. As previously stated, two principal purposes of the hinge guard embodying the invention are to limit or snub the swinging movement of the door 12, and to prevent the insertion of the fingers or the like between the jamb 16 and edge 15 of the door when the door is being closed.

My hinge guard is designated generally by the numeral 17 and comprises an elongated, continuous, unitary strip or band 18 formed of rubber, synthetic rubber or like resilient and somewhat flexible material. As shown in Figure 3, the hinge guard 17 may extend for the entire height of the door adjacent to the door jamb, and, if desired, the guard may extend over any chosen portion of the height of the door. As shown in Figure 3, the hinge guard 17 is preferably of uniform width throughout its entire length.

In Figure 1, the hinge guard 17 is shown in its natural or preformed shape which the guard assumes while disconnected from the door and door frame jamb. The hinge guard is composed of a plate-like body or strip having a portion 18 along one side which is flat or planar and relatively thin and of uniform thickness. The laterally outward edge of the portion 18 is gradually increased in cross section to provide an outwardly flaring longitudinal side portion 19 of substantially increased thickness with respect to the portion 18. On the outer edge of the portion 19 is integrally formed a narrow flange 20 extending at an acute angle to the portions 18 and 19 at the outer side thereof. The flange 20 extends

for the entire length of guard 17, or for the entire height of door 12. Flanges 20 is preferably of substantially the same thickness as the portion 19 of the band. When freely disposed in the normal preformed position, the flange 20 will assume the position shown in Figure 1. A fillet 21 connects the flange 20 and the portion 19, and the thickness of the guard at this fillet is preferably greater than the thickness of the flange 20 and portion 19. The outer face or 10 side 22 of the flange 20 is flat, as shown; and a substantially rigid, flat, metal anchoring plate 23 is molded or otherwise permanently mounted within the flange 20, as shown.

The laterally inward edge of the portion 18 merges into an arcuate portion 24 which increase in thickness toward the adjacent longitudinal side of the guard. As shown in Figure 1, the arcuate portion 24 curves toward the inner side of the guard and is substantially thicker than the section or portion 19 and flange 20 and is accordingly much stiffer and less flexible than the portion 19 and flange 20, although such portion and foot are also much stiffer and less flexible than the relatively thin portion 18 which is highly flexible, yet stiff enough to assume the normally substantially straight position of Figure 1 when the guard 17 is freely disposed or disconnected from any door. The arcuate portion 24, like the rest of the band 18, extends continuously for the entire length of the hinge guard, as illustrated in Figure 3. The guard 17 is formed on the outer edge of the portion 24 with a relatively narrow, thick, lateral flange 25 integrally connected with the portion 24 by a thick fillet 26. As shown in Figure 1, the fillet 26 is the thickest portion of the entire guard 17, and this fillet is substantially rigid or stiff, yet possesses some flexibility and resiliency. The flange 25 extends substantially at right angles to the outermost or thickest portion of the arcuate portion 24, laterally outwardly beyond one side of the arcuate portion 24. The outer side 27 of the flange 25 is flat, as shown, while the opposite side thereof has an irregular contour, forming a longitudinally extending hump or bead 28 and an outer somewhat reduced terminal edge 29. The flange 25 is thus somewhat tapered transversely toward the edge 29, Figure 1. A flat, substantially rigid anchoring plate 30 is molded or otherwise permanently embedded within the flange 25, as shown, and both plates 23 and 30 are generally parallel to the faces 22 and 27, respectively. The anchoring plates 23 and 30 extend for the entire length of the hinge guard 17.

As best shown in Figure 2, the flange 20 is secured to one side of the door 12 adjacent to the inner edge 15 thereof by means of any suitable fasteners 31 which extend through apertures provided in the flange and anchoring plate 23. Any desired number of the fasteners 31 may be provided, and the fasteners are longitudinally spaced equidistantly along the flange 20. The flange 25 is likewise detachably secured to the inner side of the door jamb by means of longitudinally spaced fasteners 32 engaging through apertures formed in the strip 25 and anchoring plate 30. The flat faces 22 and 27 engage against the adjacent side of the door 12 and jamb 16, respectively, as shown. When the hinge guard 17 is thus assembled onto the door and door jamb, it will assume positions different from its normally free position

of Figure 1, as clearly shown in Figure 2. When the door 12 is opened to its fullest extent, as shown in full lines in Figure 2, the hinge guard 17 will assume a substantially transversely extended and slightly arcuate position adjacent to and spaced laterally from the edge 15 and door jamb 16. Adjacent to the flange 20, the thickened portion 19 will be deformed or bent into a substantial S-shape, as shown. The thickened section 24 will retain substantially its normal arcuate shape, although it will be somewhat straightened and bent inwardly toward the adjacent jamb 16. In the position shown in full lines in Figure 2, substantially the entire hinge guard 17 is under tension, and the hinges 13 are substantially completely enclosed between the hinge guard and door jamb and edge 15.

When the door 12 is swung to its completely closed position, shown dotted in Figure 2, the central, relatively thin portion of the band 18 will flex for forming an elongated, narrow loop or roll 33. The arcuate section 24 will become substantially straightened and disposed substantially perpendicular to the jamb 16. The thickened portion 19 will lose its S-shaped configuration shown in full lines in Figure 2, and assume a substantially U-shaped configuration forming a loop or roll 34, shown dotted in Figure 2. This U-shaped loop or roll 34 is quite narrow, as is the roll 33, as previously stated, and the relatively thin, flexible, central portion of the band 18 will lie substantially flat adjacent to the inner side of the closed door 12. Such central portion of the band 18 will be arranged substantially perpendicular to the door jamb 16, as shown dotted in Figure 2. The arrangement is such that the entire hinge guard 17 assumes a folded, compact and narrow position adjacent to the inner side of the closed door 12, and substantially perpendicular to the door jamb 16.

One intermediate position of the door 12 and hinge guard 17 is shown dotted in Figure 2, and the disposition of the hinge guard 17 in this intermediate position is believed to be obvious and understandable without any further detailed description of it.

By virtue of the preforming and tensioning of the thickened portion 19 and section 24, the hinge guard 17 is certain to always operate in the same manner and to assume the same positions when the door 12 is disposed in the fully opened, fully closed or intermediate positions. The thickened section 24, Figure 2, constantly urges the flexible band 18 outwardly or away from the door jamb 16, so that there is never any tendency for the highly flexible, central or intermediate portion of the band 18 to work its way into the space between the door jamb and edge 15 of the door. The thickened portion 19 serves a similar purpose at the opposite side of the guard 17, and serves to constantly maintain the band 18 spaced from the door jamb 16.

As is obvious, the width of the hinge guard 17 will determine its effectiveness as a stop or snubber for limiting the opening swinging movement of a door. The relatively thin, central portion of the band 18 can be made in any desired width, and if narrow enough, the opening movement of the door may be much more limited than the fully opened position shown in full lines in Figure 2. In the fully opened position of Figure 2, the door 12 has

induced tension into the guard 17, so that the guard will function to snub or retard the opening movement of the door 12 before it reaches the fully opened position shown in full lines in Figure 2.

In Figure 4, I have shown a modified form of the invention, wherein a hinge guard 17', similar to the hinge guard 17, is shown partly applied to a different type of hinge joint, including a swingable door or panel 12' and fixed wall or panel 11' hingedly connected by means of hinges 13'. In the form of the invention illustrated in Figure 4, the hinge guard 17' has generally the same preformed shape as the guard 17, except that the flange 25 is omitted. Instead of the flange 25, the guard 17' is provided with an arcuate, thickened portion 24' corresponding to the portion 24, and this arcuate, thickened section 24' has integrally connected therewith a flange 25' including a flat end or face 27' for engagement against the inner face of the wall 11', as shown. Otherwise, the hinge guard 17' is substantially identical with the hinge guard 17 of the first form of the invention, and the flange 20' of the guard 17' is shown disconnected from the door or panel 12', to illustrate the normal or untensioned position of the hinge guard 17'. When completely applying or assembling the guard 17' to the door 12', the flange 20' is twisted around in a counterclockwise direction, Figure 4, and secured to the adjacent side of the door 12' with suitable fasteners, not shown, similar to the fasteners 31. When thus completely assembled onto the door 12' and wall 11', the hinge guard 17' serves the same general purposes as the hinge guard 17.

It should be understood that my hinge guard and door snubber may be colored as desired to blend with the coloring of the adjacent door and door frame, and the like. Due to the fact that the hinge guard is formed of rubber or like material, it will be much more durable and less likely to fray and wear than the usual ornamental roll or trim. When applied to automobile doors, my hinge guard will form a highly effective safety device to prevent fingers from being smashed between the inner edge of the

door and door frame when the automobile door is closed. The device will also form an effective snubber or stop to limit the opening swinging movement of the automobile door. The hinge guard may be applied to any device which embodies an unprotected hinge joint, such as certain trunks, suitcases, crates and the like.

It is to be understood that the forms of my invention herewith shown and described are to be taken as preferred examples of the same, and that various changes in shape, size and arrangement of parts may be resorted to without departing from the spirit of the invention or the scope of the subjoined claim.

Having thus described the invention, I claim:

In a guard for bridging the space between a door jamb and the adjacent edge of a door hinged on the door jamb, a resilient plate elongated in the direction of the length of the door and door jamb, said plate having longitudinal side edge portions, one of said side edge portions comprising a portion of greater thickness than the intermediate portion of said plate and a first flange projecting laterally from one side of the plate, said first flange being adapted to be engaged with and secured to the door jamb, the other of said side edge portions comprising a portion of greater thickness than said intermediate portion of said plate and thinner than said first side edge portion and a second flange projecting laterally from said plate on the said one side of the plate, said first flange having an outer side remote from said second flange and said second flange having an outer side remote from said first flange, the outer side of said first flange being adapted to be engaged with and secured to the door jamb at one side of said space and the outer side of the second flange being adapted to be engaged with and secured to the door at the other side of said space.

NOBLE E. FEELER.
